HANDBAG

William H. Hardy, River Edge, N. J.

Application August 1, 1951, Serial No. 16,102

Term of patent 14 years

(Cl. D87—3)

To all whom it may concern:

Be it known that I, William H. Hardy, a citizen of the United States, residing in River Edge, in the county of Bergen and State of New Jersey, have invented a new, original, and ornamental Design for a Handbag, of which the following is a specification, reference being had to the accompanying drawing, forming part thereof.

Fig. 1 is a perspective view of a handbag embodying my new design, showing the top section of the handbag in an open position;

Fig. 2 is a similar view but showing the bottom section of the handbag in an open position;

Fig. 3 is a rear perspective view illustrating both sections slightly open;

Fig. 4 is a front elevational view of the handbag on an enlarged scale; and

Fig. 5 is an enlarged top plan view of the handbag.

I claim:

The ornamental design for a handbag, substantially as shown.

WILLIAM H. HARDY.
